UNITED STATES PATENT OFFICE.

CHARLES D. LANNING, OF BOSTON, MASSACHUSETTS.

CURRENT-TRANSMITTING INSTRUMENT.

1,073,692.

Specification of Letters Patent. Patented Sept. 23, 1913.

Application filed June 5, 1907. Serial No. 377,313.

To all whom it may concern:

Be it known that I, CHARLES D. LANNING, a citizen of the United States, residing in Boston, in the county of Suffolk and State of Massachusetts, have invented an Improvement in Current-Transmitting Instruments, of which the following description, in connection with the accompanying drawings, is a specification, like letters on the drawings representing like parts.

My invention relates to telephone instruments for transmitting electrical current and more particularly, though not exclusively, to repeating instruments of the granular microphone type for repeating, re-laying, or reinforcing telephone currents.

This invention aims, generally, to improve instruments of this type by providing simple and effective means for preventing the packing of granules between the electrodes of the microphone, said packing being an inherent defect of instruments employing granular carbon and impairing and diminishing the efficiency thereof. The above, however, with other features and objects of my invention will be best understood and appreciated by reference to the following description, when taken in connection with the accompanying drawings, of a repeating instrument embodying one form of my invention and selected for purposes of illustration, its scope being more particularly pointed out in the appended claims.

In the drawings; Figure 1, is a plan view of a repeating instrument embodying one form of my invention; Fig. 2, a side elevation of the same, partially in vertical section on the line 2--2, Fig. 1; Fig. 3, an end elevation, from the right Fig. 1; Fig. 3^a, a detail of the arm for turning the microphone; Fig. 4, a diagrammatic representation of a telephone circuit embodying my invention to represent the switch mechanism employed for rendering the antipacking mechanism inoperative upon the establishment of through connections. Figs. 5 and 6, are similar views of modified forms of switch mechanism that may be substituted for that shown in Fig. 4; and Fig. 7, a telephone system showing a modified arrangement of repeating circuits to which reference will be made.

Referring to the drawings and more particularly to the selected embodiment illus-

trated in Figs. 1 to 3, there is shown a repeating instrument for repeating the current undulations of a main line circuit or from one circuit to a second circuit. As the circuit connections of this type of apparatus are well known to those skilled in the art, the same are not herein specifically shown and may be but briefly described.

In the present instance, one side, *a*, of the main line circuit, Fig. 4, preferably a metallic circuit, is serially connected to the binding posts 1, 1', Fig. 1, which as herein shown, are connected with the energizing coils 2 of a receiving magnet 3, while the other side, *b*, of the main line circuit, through which the current undulations of the first are repeated or transmitted, with intensification to the distant listening or receiving station, is connected in series with the binding posts 4, 4', the latter being in series with the terminals of the finely wound secondary of an induction coil 5. The primary winding of this coil is in what is herein denominated the repeating circuit, *c*, and connected to a third set of binding posts, 6, 6', the latter being in series with a suitable source of electrical energy, such as a battery 7, Fig. 4, the repeating circuit, *c*, in passing from the induction coil to the binding post 6', including the variable resistance transmitting instrument or microphone 8, by means of flexible conductors 9, 9', attached respectively to the movable and fixed electrodes thereof.

Considering first the receiving electromagnet 3, the latter is so constructed and operatively related to the microphone as to transmit magnetic variations to the repeating circuit with a minimization of the waste of effort. To produce as effective a magnetic field as is possible from the variable line energy of the main line circuit, said magnet is provided with an armature 10, which is closely associated with the core of the magnet, so as to provide a substantially complete magnetic circuit only interrupted by such an air gap as is essential to permit suitable vibratory movement of the armature. As herein shown, said magnet, 3, is preferably of the magnetized horse shoe type commonly employed in telephone instruments, the arms of the magnet receiving the line magnetization coils 2, which are placed at the extreme end thereof, so that prac-

5 tically their entire magnetization power is directly effective upon said armature with as little leakage as possible. These coils may be of elongated or elliptical shape, as shown in Fig. 2, to permit the pole pieces of the magnet to be brought close together and to reduce the diameter of the armature required to span them. While the initial magnetization of said magnet may be produced by constantly excited magnetic coils, I prefer, as herein shown, to provide a permanent magnet, of sufficient power to secure positive excitation of the magnet for all current undulations of the telephone line.

10 15 The magnet is adjustable longitudinally or toward and from the armature and is secured in desired adjustment and maintained in horizontal position upon a suitable upright support 11, Fig. 2, by means of a 20 preferably non-magnetic clamping plate 12, and clamping screw, 13, said support 11 being suitably secured to the baseboard 14 of the instrument.

25 To provide an armature of relatively low magnetic reluctance, the latter is preferably of block form, herein preferably disk shaped and preferably laminated to eliminate eddy currents, the dimensions of the armature being such as to provide a suitable path for 30 the magnetic flux of the magnet and an armature—electrode of relatively light weight and low inertia. As shown in Figs. 1 and 2, this armature is normally in a 35 magnetic relation to the magnet and in a position to be most effectively operated thereby. As thus constructed, a highly efficient armature is provided that responds readily to the energization current of the main line circuit and is effective to produce 40 the best results in actuating the microphone to which it is operatively connected.

45 In the present instance, the microphone employed is of the granular carbon type, such for example, as the solid back microphone transmitter shown in the drawings, Figs. 1 and 2. As is well known, this type of microphone ordinarily comprises a suitable cylindrical casing 15, Fig. 2, within which is what is termed the "resistance button." As herein shown, this resistance button comprises a relatively fixed or stationary carbon electrode 16 at the bottom of the customary button receiving or carbon chamber with which microphones of this type are 50 provided, a vibratory or movable carbon electrode 17, at the outer end of said chamber, and an intermediate body of finely divided or granular conducting material, such as carbon granules 18, which are confined in said chamber between said electrodes. The stationary electrode is secured to the microphone casing and the movable electrode is connected with the described armature of the electromagnet, so that it 55 moves therewith and vibrates toward and

from the fixed electrode and thereby varies the resistance of the intermediate body of the granular carbon in a manner well understood.

60 For connecting the vibratory electrode of the microphone to the electromagnet armature, 10, any suitable means may be employed that will maintain it in definite relation to the fixed electrode and permit suitable vibratory movement, though I prefer the construction herein shown, wherein a light aluminum plate 19 is attached to the outer surface of said movable electrode, said plate being mounted upon a light diaphragm 20, herein of mica, which is secured by its periphery to said casing by means of a suitable retaining and clamping ring 21. This diaphragm is centrally provided with an outwardly projecting stem 22, which is secured by an insulating collar 23 at its outer 65 end to the back of the electrode armature.

70 By this construction the vibratory-electrode 17 is supported in operative relation to its co-operating stationary electrode 16 and the vibratory or microphonic movement, 75 essential to the efficient operation of the microphone, is readily permitted, the said electrode having a plunger-like movement within the carbon chamber to produce current variations in the primary circuit in a 80 manner well understood, which through the secondary winding of the induction coil are transmitted to the main line and, in the present instance, with a desired amount of 85 intensification. The device is thus especially adapted for use as a repeater, relay, 90 or reinforcing instrument in repeating or reinforcing circuits.

95 The microphone is mounted upon an adjustable support to permit it to be moved toward and from the electromagnet for 100 varying the amount of air gap and to provide a suitable transverse movement for centering the microphone with reference to the line of magnetic pull produced by the magnet on its armature. To this end, the inner 105 end of the casing is provided with a projection 24 which is secured in the forked end of a relatively massive revoluble shaft 25 by means of a clamping screw 26, said 110 shaft being suitably journaled in a pair of uprights 27 carried by a block 28. This block is mounted to slide transversely in a supporting block 29 mounted for longitudinal adjustment between standards 30. The 115 transverse adjustment of the inner block 28 is permitted by providing the block 29 with suitable ways 31, said adjustment being effected by means of a transverse adjusting screw 32 in threaded engagement with a block 28 and rotatably mounted at its ends in said block 29 and provided with a lock nut 32a. By this construction, the screw 120 may be turned to produce movement of the connected block 28 relative to the carrying 125 block 29.

block 29, so that it may be moved from one or the other side of the axis of the magnet to present the armature in desired central position relative to the pole pieces of the magnet.

5 To secure longitudinal adjustment of the microphone, the block 29 is longitudinally threaded to receive an adjusting screw 33. The latter is journaled at 34 in the standards 30 of the base board, and by rotating the screw, said block may be moved toward and from the magnet and secured in any adjusted position by means of a lock nut 35 upon the engaging threads formed on the outer and reduced end of the screw.

10 In repeating and relaying instruments of this type wherein granular carbon is employed, and to a lesser extent also in the ordinary granular carbon transmitter, there is a tendency of the granules in the carbon chamber to pack, said packing impairing the resistance varying properties of the carbon mass in responding to the relative vibrations of the electrodes and terminate the 15 transmitting efficiency of the instrument. This packing of the carbon granules, a defect inherent in instruments of this type, is principally due to the gravitation of the granules to the bottom of the carbon chamber and the present invention provides suitable means for restoring the granules to their normal unpacked condition between the electrodes so as to render the instrument more effective. To this end and in the 20 present instance of my invention, the transmitter is periodically rotated successively to bring such portions of the carbon chamber in which the granules tend to pack to the top of the instrument, which effects dis- 25 placement, loosening, and consequent unpacking of the granules, thereby restoring them to their normal unpacked, loose condition.

25 Referring more particularly to Figs. 1 and 3, the revoluble shaft 25 which at its inner end carries the microphone is provided intermediate said uprights 27 with a rocking arm 36, the hubbed end of which is loosely mounted on said shaft. The shaft bearing surface of this hub, however, is provided with a longitudinally extending notch 37, Figs. 3, 3^a wedge shaped in cross section. Arranged in this notch is a plurality of friction balls 38, which permit the arm to be 30 turned freely in one direction, upward, Fig. 3, the balls gravitating toward the small end of the notch, but when its outer end is swung downward produce a gripping action upon said shaft to cause the latter to turn 35 with it. This arm is oscillated back and forth periodically, so that the carbon granules in the carbon chamber of the microphone are intermittently distributed or restored to their normal loose condition thus 40 effectively preventing the packing thereof.

The shaft 25 is provided with a collar 25^a which bears against the outer surface of the left upright, 27, Fig. 1, and the opposite end of said shaft extends beyond the right upright 27 and is exteriorly provided with a 45 surrounding stiff coil spring 39 which is interposed between the milled head of said shaft and a washer 25^b also on said shaft and bearing against the outer face of the right upright 27. This spring 39 normally maintains the shaft 25 in the position shown in 50 said Fig. 1, and prevents any longitudinal movement of said shaft or of the microphone casing when the armature-electrode of the latter is vibrated by the action of the electrode magnet 3. By this arrangement, the microphone is maintained in predetermined magnetic relation to the electromagnet while revoluble movement thereof is freely permitted. To provide suitable means for producing this oscillating movement of the arm 36, I preferably provide a local circuit *d*, best shown in Fig. 4, connected to the binding posts 40^a and in which is a vertical electromagnet 40 mounted upon said baseboard 55 14, the magnet poles being in close association with a suitable armature 41 upon the free end of said lever. The coils of this magnet are energized by a suitable source of electrical energy, such as a battery 42 arranged in series in said local circuit, and it will be obvious as long as the circuit is closed that the magnet will cause the depression of the outer end of said lever and hold it down upon the magnet until the circuit is broken. The armatured end of said lever, Fig. 3, is 60 normally maintained in elevated position by a coil spring 43 connecting the same to a suitable standard 44 upon the base, 4, said spring yielding to permit depression of said arm when the local circuit is closed and elevating it when the circuit is broken. To open and close this local circuit periodically, so that the microphone may be intermittently rotated, said circuit is provided with 65 current interrupting and closing means which obviously may be of any suitable construction, but as herein shown, comprise a suitable clock work 45, which causes the revolution of an outer circuit making and breaking wheel 46, the periphery of which is provided with insulating and conducting surfaces 47, 48. In suitable relation to the periphery of this wheel, herein at one side thereof, Fig. 4, is a suitable contact spring 70 49, one terminal of the local circuit being connected therewith and the other to the metallic or conducting surfaces of said wheel. In operation, the rotation of said wheel, 75 brings the contact point of the spring into successive contact with conducting and insulating surfaces thereof, thereby respectively opening and closing the local circuit to cause, through the electromagnetic action of the magnet 40 upon its armature 41, the 80 125 130

periodic oscillation of the arm 36 and the consequent periodic turning movement of the microphone. The relative number of insulating and conducting surfaces upon the 5 periphery of said wheel may obviously be varied to produce as many unpacking movements of the microphone as is desired, my invention not being limited in this respect, but in any event such movement is made to 10 occur with sufficient frequency as to practically eliminate packing.

To provide suitable means for preventing the periodic revoluble movement of the microphone, while the repeating instrument 15 is operating or to express it differently, while the line is in use, any suitable means may be employed, though in the present instance I prefer to provide switch mechanism for breaking the local circuit upon the establishment of through connections. To this 20 end and referring to Fig. 4, wherein the repeating instrument is shown preferably at an intermediate station, the through connections being established by inserting the 25 usual type of switch plug 50 in its spring jack 51, said jack having the usual contact spring 52 herein shown as provided with an insulated contact plate 53 connected to one terminal 54 of the local circuit, the other 30 terminal of said circuit being connected to a suitable contact 55 normally engaged by said switch spring plate when the plug is removed. It will be observed from this arrangement that the insertion of the plug in 35 its jack elevates the contact spring and breaks the local circuit, thus stopping the periodic anti packing movement of the microphone while the line is busy.

In Fig. 5, the local circuit leads to a receiving station and is connected with the switch hook upon which the receiver is normally hung when not in use, the terminals of the local circuits being connected one to an insulated plate, 56, upon the usual spring 45 controlled switch hook, 57, and the other to a suitable contact, 58, engaged by said plate, when the receiver is hung up. In taking down the receiver, the switch hook is elevated by its spring and the local circuit is 50 broken, so that the microphone is not turned during the use of the instrument.

Referring now to the modification of switch mechanism represented in Fig. 6, the local circuit is provided with a spring controlled switch lever 60 pivotally and sensitively mounted intermediate its ends upon a suitable support 59. The right end of this switch lever normally rests upon the contact 61, to which one terminal of said local circuit is attached, the other being directly attached to said switch lever. The contact end of this lever is also provided with a light spring arm 62, which normally acts to depress the contact of said lever upon cooperating contact, 61, thus maintaining the cir-

cuit closed. The opposite end of this switch lever is provided with a suitable armature plate 63 beneath which is an electromagnet 64 in series with the main line circuit. By this construction, it will be apparent that when any current flows in the main line, the electromagnet 64 will attract the armatured end of said switch lever and depresses it thereby breaking the local circuit in which the means for operating the antipacking device are located. It is of course, understood that the current in the main line is of an alternating character but the alternations are relatively high in periodicity and the character or normal rate of vibration of the spring 62 employed for maintaining the switch lever in circuit closing relation is not such as to permit of its responding to such a high rate of oscillation, so that the armatured end of the lever will be pulled down by the electromagnet, to keep the circuit open as long as the current flows in the main line circuit.

While these three modifications, herein shown as illustrative of suitable means for breaking the local circuit, differ in construction, one being under the control of an intermediate operator, who establishes through connection, the second under the control of the person who takes down the receiver at 90 one of the talking stations, and the third actuated by the voice caused currents of the main line circuit, it will be apparent that all are made operative by the establishment of through connections between the talking 95 stations thus providing effective means for breaking the local circuit and preventing antipacking movement of the microphone while the line is in use. If desired, however, the switch mechanism may obviously be 100 omitted and the intermittent action of the antipacking mechanism continued during the use of the line, so that there may be no effective packing action of the carbon granules in the microphone during any extended 105 use of the latter.

The circuit connection of the apparatus employed at the terminal stations being of the usual construction, no description need be given except to say that the terminal stations are provided with receiving and transmitting instruments conventionally represented as in Fig. 4, for example, as comprising the receiver 65, the transmitter 66, the latter being in local circuit with a battery 110 67 and the primary winding of antinduction coil 68, a secondary of which is in series with the main line circuit and the receiver.

In Fig. 5, the circuit arrangement at but one circuit station is shown and is sufficient 115 since that at the other terminal is a mere duplication thereof. In Fig. 6, wherein the switch mechanism is preferably at an intermediate repeating or relaying station, the main circuit wires lead to the usual terminal 120 130.

stations where the circuit connections (not shown) are the same as shown in Fig. 4.

In the telephone system shown in Fig. 4, the operated circuit of the telephone repeating instrument is directly in series with one side, *a*, of the main line circuit, so that the original voice actuated currents produce corresponding variations of magnetic action in the receiving magnet, which produces 5 through actuation of the microphone, undulations in the repeating circuit harmonious and proportional to the original voice caused current undulations of the main circuit. The current undulations in the repeating circuit, *c*, through the action of the induction coil, 5, therein, are in turn induced upon the main line circuit, but in the present instance, upon the opposite side, *b*, thereof, hence there is no direct or inductive relation 10 between said sides, thus avoiding all the characteristics of bridged repeating circuits or instruments. It will be obvious to those skilled in the art, that by this arrangement the repeated current undulations in the repeating circuit are reimpressed upon the main line circuit and are cumulative with the original voice actuated current undulations thereof and with no substantial loss of energy, since there are no divided circuits or 15 bridge devices to split up the current energy, so that the whole of the latter is effective in the repeating instrument and is thereby transmitted to the main line.

While in Fig. 4 the telephone repeating instrument and the operating and operated circuits thereof are in direct serial relation with the main line circuit, the operated circuit with one side and the operating circuit with the other, my invention obviously is not limited thereto, and comprehends placing the operating and operated circuits in inductive relation to the opposite sides of the main line as shown in Fig. 7, but in any event serially, so as to avoid 20 bridge arrangements and the splitting of the current, and thus utilize the entire energy of the line.

Referring to Fig. 7, the circuit arrangements are but conventionally represented, 25 and include two separate reinforcing circuits each containing a repeating instrument of the type described, the two repeating circuits being reversely arranged between the sides of the main line circuit and each 30 preferably constituting a repeating or re-laying station between the receiving or transmitting stations. In the present instance, what may be termed the operating circuit of the repeating instrument includes 35 the receiving magnet 3, which is serially and inductively related to the main line and operated by the current variations thereof to actuate the current varying medium or transmitting element represented 40 at 8. This current varying medium or

transmitting element, preferably herein of the granular carbon type described, upon being actuated by the receiving magnet produces current undulations in the repeating or operated circuit of the instrument, 70 which I term the operated circuit thereof not only because it is operated by said receiving magnet but because through induction coil in series with said circuit, it induces or transmits to the main line circuit, 75 the current undulations produced therein in the repeating circuit which are, as will be well understood, proportional and harmonious to the original voice caused current undulations of said main line circuit. 80

My invention provides a repeating or re-laying circuit and repeating instruments that are effective to respond to impulses or efforts in every direction with equal sensitivity and without appreciable distortion of the reproduced sound. The construction of the electromagnet actuator and the co-operating diaphragm of the microphone eliminate all wasteful mechanical effort and secure a direct magnetizing effort 90 between them, so that the pull of the magnet, the diaphragmatic pull and the resulting movement of the electrode are all coincident and act as co-ordinate actors to transmit magnetic undulations primarily to 95 the electrode and make the latter delicately responsive thereto. The effective action of the repeating instrument and its delicate responsiveness to the energizing current of the main line circuit would be ineffective to 100 produce the best results without the described means for preventing the packing of the granules in the carbon chamber, the arrangement for securing this result maintaining the instrument in normal effective 105 condition at all times so that it is always ready for instant use.

Where I refer to the repeater-receiver element and the repeater-transmitter element as being magnetically independent 110 each of the other, I refer to freedom from substantial operative interference, and ordinarily (since the coils necessarily have magnetic cores) a separation of the magnetic cores of the respective elements such 115 that the magnetic flux set up by the receiving instrument is not directly operative upon the transmitting element, the latter being designed to be controlled by an independently created magnetic flux.

While I have described my invention with 120 relation to one specific embodiment thereof which has been selected for purposes of illustration herein, it is to be understood that my invention is not limited thereto, nor 125 to the specific details of construction and arrangement, but may be widely varied, and the numerous features herein involved and which evidently possess novelty, may be employed either singly or without the re- 130

maining feature or features herein disclosed, without departing from the spirit of my invention.

I claim—

5. 1. A current transmitting instrument having a receiving circuit, a receiving magnet therein, a transmitting circuit, a granular microphone in said transmitting circuit having a vibratory electrode operatively related to and actuated by said receiving magnet, and means for periodically rotating said microphone to maintain the granules in loose condition.
10. 2. A current transmitting instrument having a receiving circuit, a receiving magnet therein, a transmitting circuit, a granular microphone in said transmitting circuit having a vibratory electrode operatively related to and operated by said receiving magnet, and means for periodically disturbing said microphone to maintain the granules in loose condition.
15. 3. In a telephone system, a main line circuit provided with terminal stations, a current transmitting instrument therefor comprising a revoluble microphone provided with a vibratory electrode, a fixed electrode and an intermediate body of granular carbon and means for intermittently producing rotary movement of said microphone to maintain the said carbon granules in unpacked condition, and means controlled by the establishment of through connections between talking stations of said main line circuit for preventing operation of said rotating means.
20. 4. A telephone repeating instrument comprising a main line circuit, an electromagnetic actuator serially related thereto, a current varying microphone actuated thereby and also serially related to said line and provided with a fixed electrode, a vibratory electrode and a body of granular carbon intermediate said electrodes, means for revolubly mounting said microphone to maintain its vibratory electrode in magnetic operative relation to said magnet, means for intermittently rotating said microphone to maintain the said granules in unpacked condition, and means under the control of an operator for rendering said intermitting means inoperative.
25. 5. A telephone system having a relay provided with a receiving magnet, a microphone actuated thereby provided with a variable resistance medium, such as carbon granules, means for intermittently restoring said granules to their normally loose condition to prevent packing thereof, and means rendered operative by the establishment of through connections between stations of said system for rendering said restoring means inoperative while the instrument is in use.
30. 6. In a device of the type described, a granular carbon microphone, a rotary shaft

to which said microphone is secured, means for revolubly supporting said shaft, an arm loosely mounted on said shaft and adapted to be clutched thereto for revolving said shaft, and a local circuit having an electromagnet in magnetic relation to said arm, a source of electrical energy, and circuit interrupting means for periodically opening and closing said circuit and intermittently rotating said shaft and its connected microphone.

7. In a device of the type described, a movable support 29 provided with uprights, 27, a shaft, 25, revolubly mounted therein and having a microphone of the granular carbon type secured to one end thereof and a loosely mounted arm 36 adapted to be clutched thereto to cause rotary movement of said shaft upon oscillating said arm, and a local circuit and connected devices for intermittently oscillating said arm and revolving said shaft and said microphone.

8. In a telephone system, a main line circuit, a repeating instrument having an electromagnetic actuator in electromagnetic relation to but one side of said main line circuit, and electromagnetic means, in non-inductive relation to said actuator, in inductive relation with the opposite side of said line and operated by said actuator.

9. In a telephone system, a main line circuit, a repeating circuit in electromagnetic relation to but one side of said main line circuit, said circuit containing a microphone and a source of electrical energy, and an electromagnetic device operated by the current variations of said main line circuit and in inductive relation to the other side thereof for actuating said microphone.

10. In a telephone system, a main line circuit, a repeating circuit in series relation to but one side of said main line circuit, said circuit containing a granular carbon microphone and a source of electrical energy, an electromagnetic device operated by the current variations of said main line circuit and in inductive relation to the other side thereof for actuating said microphone and means for periodically agitating said microphone for maintaining the carbon granules thereof in normal or unpacked condition.

11. In a telephone system the combination with a main line circuit and terminal stations of an intermediate repeating station having a repeating circuit, an electromagnetically controlled microphone in the same of the granular carbon type, and means independent of the condition of the carbon granules for automatically maintaining the same in unpacked condition.

12. In a telephone system, a main line circuit provided with terminal stations, an intermediate repeating station having a repeating circuit, and an electromagnetically controlled microphone of the granular car-

70.

bon type, anti-packing means to prevent packing of the carbon granules, and means dependent upon the employment of the repeating apparatus at the repeating station 5 in the ordinary use of the main line circuit for controlling the operation of said anti-packing means.

13. In a telephone system, a main line circuit provided with terminal stations and an intermediate repeating station, the latter having a repeating circuit and a microphone of the granular carbon type, anti-packing means for preventing the packing of the carbon granules, and means for controlling 15 the operation of the anti-packing means by the discontinuance or resumption of service on the main line.

14. In a telephone system, the combination with a main line circuit and terminal stations of an intermediate repeating station having a repeating circuit and an electromagnetically controlled, solid-back microphone in the same, and means for automatically moving the microphone to maintain the 25 carbon granules in unpacked condition.

15. The combination with a telephone line having a 2-way metallic circuit, of a repeating apparatus provided with magnetically independent receiving and transmitting elements, operatively related to each other, the operating circuit of the receiving element being in series relation to one side only of the main line circuit and the operated circuit of the transmitting element being in 35 series relation to the other side only of the said main line circuit.

16. In a telephone system, in combination with a metallic circuit, current reinforcing instrumentalities comprising magnetically independent receiving and transmitting elements, the former operatively related to the latter; the said receiving element being serially related to one side only of said circuit and the said transmitting element being serially related to the other side only of said circuit.

17. In a telephone system, in combination with a metallic circuit, current reinforcing instrumentalities comprising a pair of symmetrically placed reinforcing devices, each comprising a receiving and a transmitting element that are operatively related the first to the second and are magnetically independent, a receiving element, of one and a transmitting element of the other of the pair being serially and magnetically independently related to each side of said circuit,

said elements being each serially related to one side only of the main line circuit.

18. In a telephone system, in combination 60 with a metallic circuit, current reinforcing instrumentalities comprising receiving and transmitting elements, the former operatively related to the latter; the said receiving element being serially related to one side 65 only of said circuit and the said transmitting element being serially related to the other side only of said circuit.

19. In a telephone system, the combination 70 with a transmitting and a receiving device and an intermediate continuous main line circuit of a repeating circuit, means serially associated with one side only of the main line circuit for producing current variations in the repeating circuit to correspond 75 to energy variations in the telephone circuit and means inductively related to the repeating circuit but not inductively associated with the current-variation-producing means for reinforcing the energy passing 80 through the said current-variation-producing means, said reinforcing means being serially related to the other side only of the main line circuit.

20. In a telephone system, in combination 85 with a transmitting and a receiving device and a continuous main circuit line between the same, of a repeating circuit inductively related to one side only thereof, a current varying medium associated with said repeating circuit, and means serially associated with the other side only of the said line circuit to actuate said current-varying medium for reproducing current undulations 90 over the line circuit in the repeating circuit. 95

21. In a telephone repeating system, the combination with a main line metallic circuit of transmitting and receiving apparatus at the terminals thereof; a repeater intermediate said terminals having a coil in series with one side of said circuit; a local battery and coil associated with said repeater; and a third coil in inductive relation with said second mentioned coil and in series with the other side of said circuit, 105 substantially as described.

In testimony whereof, I have signed my name to this specification, in the presence of two subscribing witnesses.

CHARLES D. LANNING.
